poration of Ohio

Application June 3, 1936, Serial No. 62,992

Term of patent 14 years

To all whom it may concern:

Be it known that I, Donald G. Smellie, a citizen of the United States, residing at Canton, in the county of Stark and State of Ohio, have invented a new, original, and ornamental Design for a Casing for a Suction Cleaner or Similar Article, of which the following is a specification, reference being had to the accompanying drawing, forming a part thereof.

The figure is a perspective view of a casing for a suction cleaner or similar article embodying
my new design.

I claim:

The ornamental design for a casing for a suction cleaner or similar article, as shown.

DONALD G. SMELLIE.
